UNITED STATES PATENT OFFICE

ERD V. CROWELL, OF LOS ANGELES, CALIFORNIA

TUBING ANCHOR

Application filed May 5, 1930. Serial No. 450,012.

This invention is a tubing anchor, and has for an object to provide a string of well tubing with a plurality of vertically spaced anchoring means adapted to anchor a tubing string at a corresponding plurality of vertically spaced points, thereby augmenting the safety factor and insuring a positive and reliable anchoring engagement such as will prove adequate for the ever increasing length of tubing strings such as are employed in modern deep wells.

It is a further object of the invention to provide a tubing string with a plurality of vertically spaced anchoring means with one of said anchoring means actuated in usual manner, and the anchoring means which is vertically spaced thereabove actuated by the anchoring engagement of the first mentioned anchoring means.

It is a still further object of the invention to provide a string of tubing with a plurality of vertically spaced anchoring means with one of said anchoring means adapted to anchor the lower portion of the tubing in usual manner, and the upper portion of the tubing adapted to telescope relative thereto and actuate the anchoring means which is vertically spaced above the first mentioned anchor.

It is a still further object of the invention to provide an anchoring means which may comprise an accessory adapted for mounting in a tubing string in vertically spaced relation from a usual anchor, so that the auxiliary anchoring means may cooperate with the usual anchor to provide anchoring engagement at a plurality of vertically spaced points.

Further objects of the invention will be readily understood from the following description of the accompanying drawing, in which:

Fig. 1 is a partial axial section through the invention, showing the anchor in inoperative position.

Fig. 2 is a similar view showing the anchor in operative position.

Figs. 3 and 4 are transverse sections on the lines 3—3 and 4—4 respectively of Fig. 1.

In the drawing I have shown a usual

tubing string 1 adapted for lowering in well casing 2, with the tubing string provided with a usual anchor which in the illustrated embodiment is adapted for either manual actuation at any desired level or automatic operation in the event of the tubing breaking.

As an instance of this arrangement a length of tubing 3 is incorporated in the tubing string 1 and may be connected to the depending portion of the tubing string by a usual coupling 4; and a head is formed on the tubing length 3 and comprises wedging elements 5 which cooperate with normally inoperative slips 6 so that relative axial movement between the wedging elements and the slips will operatively expand the latter for anchoring engagement with the wall of the well casing as shown in Fig. 2. The slips are preferably mounted on their cooperating head by means of a supporting sleeve 7 which is slidable on tubing 3, and a spring 8 which is mounted between sleeve 7 and the coupling collar 4 is normally compressed by the weight of the slips for relative axial positioning of the slips and their wedging elements whereby the slips are free to contract to inoperative position as shown in Fig. 1; but if the string of tubing drops suddenly the spring 8 tends to retard the fall of sleeve 7 so that the slips carried thereby are operatively expanded by relative axial movement of their cooperating wedging elements as shown in Fig. 2.

Manual operation of the anchor is preferably controlled by a sleeve 9 slidable on the tubing string below sleeve 7, but yieldably held against rotation or axial displacement relative to casing 2 by bowed springs 10. The sleeve 9 has a slot 11 opening through the lower end of the sleeve and forming at its upper end a transverse slot 11^a which terminates in a depending slot 11^b; and a pin 12 which projects radially from the tubing string, preferably at the coupling collar 4, is slidable in said slots and when engaging slot 11^b locks sleeve 9 against elevation relative to the tubing string as shown in Fig. 1, but by slight elevation and subsequent circumferential shifting of the tubing string relative to sleeve 9, the pin 12 is adapted for alignment with vertical slot 11 so that the tub-

ing string may be lowered relative to the sleeve, thereby impinging the sleeve 9 against sleeve 7 for elevating the slips 6 relative to their wedges 5 and thus operatively expanding the slips to anchoring position as shown in Fig. 2.

In order to provide an adequate anchoring engagement for a tubing string of such length and weight that a usual anchor such as has been described will not provide the desired safety factor, the present invention provides additional anchoring means for the tubing string, with the auxiliary anchor preferably spaced vertically above the primary anchor, and in the present instance shown as a unitary structure comprising an accessory adapted to be incorporated in a usual tubing string.

As an instance of this arrangement a tubing length 17 telescopes at its lower end in a barrel 14 which is adapted for ready assembly in the tubing string by threading the lower end of the barrel onto usual threads 13 at the upper end of tubing length 3, and the upper end of tubing 17 forms a coupling 18 adapted to engage the upwardly projecting portion of the tubing string. A head comprising wedging elements 19 is formed on tubing length 17, and slips 20 which are mounted on the head and carried by a ring 21 slidably mounted on tubing 17, are adapted for axial movement of the wedging elements relative thereto so as to contract or expand the slips as shown in Figs. 1 and 2 respectively.

As the tubing string is lowered or withdrawn from a well the weight of the lower portion of the string expands the tubular support consisting of the telescopic sections 17 and 14—3, to its limit of movement as determined by a head 16 of tubing 17 engaging a cooperating seat 15 of barrel 14, and with the parts in this position a spring 22 which is mounted between ring 21 and barrel 14 yieldably supports slips 20 so that they are in inoperative position below their cooperating wedging elements 19 as shown in Fig. 1. When the slips 6 anchor the tubing length 3, either manually or automatically as previously described, the weight of the upwardly projecting portion of the tubing string telescopes tubing 17 in barrel 14, with the spring 22 yieldably supporting the slips 20 against depression so that they are operatively expanded by the relatively axial shifting of their cooperating wedging elements 19, and the slips 20 thus provide anchoring means for the tubing string functioning as an auxiliary to the anchor formed by slips 6, with the operation of this auxiliary anchor yieldably cushioned by the spring 22 so as to avoid setting the auxiliary anchor so abruptly or so tightly as to split the casing 2 or prevent subsequent ready release of the anchor.

As previously described the tubing string must be rotated relative to sleeve 9 in order to manually actuate the anchoring slip 6,

the said rotation being obtained by turning the portion of the tubing string which projects upwardly to the earth's surface, and with head 16 engaging seat 15, the weight of the depending tubing string will bind these cooperating elements against relative rotation so that the tubing 3 may be turned by rotating the upwardly projecting portion of the tubing string, although if desired any suitable means (not shown) may be provided for positively turning the barrel 14 with tubing 17 while still permitting relative telescoping of said parts. The elements 16—15 preferably comprise a valve head and a cooperating seat adapted to engage and form a fluid tight seal when the tubing string is in normal position with its anchoring means inoperative and its telescopic parts relatively expanded, thereby preventing leakage from the tubing string during its normal use, while at the same time providing for ready contraction of its telescopic parts.

The invention thus provides a plurality of vertically spaced anchoring means for a tubing string, with one of said anchoring means preferably comprising a usual anchor, and the other of said anchoring means preferably comprising a unitary structure which may be an accessory adapted for mounting in a tubing string for use in connection with the primary anchor, and the auxiliary anchor being actuated by operative engagement of the primary anchor.

I claim:

1. A string of tubing for a well bore comprising relatively telescopic upper and lower portions having means for limiting their relative telescopic expansion whereby the lower portion may be suspended from the upper portion for insertion and withdrawal of the entire tubing string as a unit, means on the lower portion of the tubing string for anchoring said lower portion in the well bore, and means on the upper portion of the tubing string for anchoring said upper portion in the well bore, each of said anchoring means being adapted for actuation while the upper and lower portions of the tubing string are in telescopic assembled relation, and the anchoring means for the upper portion of the tubing string being adapted for automatic actuation by telescopic contraction of said upper portion with relation to the lower portion when the latter has been anchored in the well bore.

2. A string of tubing for a well bore comprising relatively telescopic upper and lower portions having means for limiting their relative telescopic expansion whereby the lower portion may be suspended from the upper portion for insertion and withdrawal of the entire tubing string as a unit, means on the lower portion of the tubing string for anchoring said lower portion in the well bore, the anchoring means being adapted for ac-

tuation by shifting the lower portion of the tubing string relative to the anchoring means, a connection between the upper and lower portions of the tubing string whereby movement of the upper portion is adapted to shift the lower portion for actuating the anchoring means, and means on the upper portion of the tubing string for anchoring said upper portion in the well bore, the anchoring means for the upper portion of the tubing string being adapted for automatic actuation by telescopic contraction of said upper portion with relation to the lower portion when the latter has been anchored in the well bore.

15 3. A string of tubing for a well bore comprising relatively telescopic upper and lower portions having means for limiting their relative telescopic expansion whereby the lower portion may be suspended from the upper portion for insertion and withdrawal of the entire tubing string as a unit, a catcher on the lower portion of the tubing string for automatically anchoring said lower portion in the well bore in the event of the tubing string dropping, and means on the upper portion of the tubing string for anchoring said upper portion in the well bore, each of said anchoring means being adapted for actuation while the upper and lower portions of 25 the tubing string are in telescopic assembled relation, and the anchoring means for the upper portion of the tubing string being adapted for automatic actuation by telescopic contraction of said upper portion with relation to the lower portion when the latter has been anchored in the well bore.

30 4. A string of tubing for a well bore comprising relatively telescopic upper and lower portions having means for limiting their relative telescopic expansion whereby the lower portion may be suspended from the upper portion for insertion and withdrawal of the entire tubing string as a unit, means on the lower portion of the tubing string for anchoring said lower portion in the well bore, the anchoring means being adapted for actuation by shifting the lower portion of the tubing string relative to the anchoring means, a connection between the upper and lower portions 35 of the tubing string whereby movement of the upper portion is adapted to shift the lower portion for actuating the anchoring means, the anchoring means being also adapted for automatic actuation in the event of the tubing string dropping, and means on the upper portion of the tubing string for anchoring said upper portion in the well bore, each of said anchoring means being adapted 40 for actuation while the upper and lower portions of the tubing string are in telescopic assembled relation, and the anchoring means for the upper portion of the tubing string being adapted for automatic actuation by telescopic contraction of said upper portion

with relation to the lower portion when the latter has been anchored in the well bore.

5. In a tubing catcher, a tubular support comprising telescopic sections, a slip cooperating with each section, means for automatically radially displacing the lower slip due to the inertia of the tubing catcher when it is dropped, whereby the lower telescopic section is anchored, and means for radially displacing the upper slip due to telescoping of the upper section relative to the anchored lower section.

70 6. In a tubing catcher, a tubular support comprising telescopic sections, a slip cooperating with each section, means for radially displacing the lower slip for anchoring the lower telescopic section, and means for radially displacing the upper slip due to telescoping of the upper section relative to the anchored lower section.

75 7. In a tubing catcher, a tubular support comprising telescopic sections, means for maintaining a fluid tight seal between the telescopic sections when in normal relatively expanded position, a slip cooperating with each section, means for radially displacing the lower slip for anchoring the lower telescopic section, and means for radially displacing the upper slip due to telescoping of the upper section relative to the anchored lower section.

80 8. In a tubing catcher, a tubular support comprising telescopic sections, a head on each section, a slip cooperating with each head, means for radially displacing the lower slip for anchoring the lower telescopic section, means for yieldably supporting the upper slip on the lower telescopic section, and means for radially displacing the upper slip by relative longitudinal movement of its cooperating head due to telescoping of the upper section relative to the anchored lower section, the yieldably supporting means for the upper slip cushioning said radial displacement of the upper slip.

85 9. In a tubing catcher, a tubular support comprising superimposed telescopic sections, a head on each section, a slip cooperating with each head, and means actuated responsive to inertia of the tubing catcher when it is dropped, for automatically and consecutively radially displacing the slips which cooperate with the heads of the successively higher superimposed sections.

100 10. In a tubing catcher, a tubular support comprising superimposed telescopic sections, a slip cooperating with each section, and means actuated responsive to inertia of the tubing catcher when it is dropped, for automatically and consecutively radially displacing the slips which cooperate with the successively higher superimposed sections.

105 In testimony whereof I have affixed my signature.
